UNITED STATES PATENT OFFICE

122,454

DESIGN FOR A JODHPUR

Joseph J. Ascheim, Boston, Mass.

Application May 22, 1940, Serial No. 92,529

Term of patent 3½ years

To all whom it may concern:

Be it known that I, Joseph J. Ascheim, a citizen of the United States, residing at Boston, in the county of Suffolk and State of Massachusetts, have invented a new, original, and ornamental Design for a Jodhpur, of which the following is a specification, reference being had to the accompanying drawing, forming part thereof.

my new design.

I claim:
The ornamental design for a jodhpur, as shown.

JOSEPH J. ASCHEIM.
